(57) **CLAIM**

The ornamental design for a combined platform and litter box, as shown and described.

DESCRIPTION

FIG. 1 is a perspective view of a combined platform and litter box showing a first embodiment of my new design, the perspective view illustrating a front, a top, and a right side thereof, a left side being a mirror image of the right side shown;

FIG. 2 is a rear view of the first embodiment;

FIG. 3 is an exploded perspective view of the first embodiment;

FIG. 4 is a perspective view of a combined platform and litter box showing a second embodiment of my new design, the perspective view illustrating a front, a top, and a right side thereof, a left side being a mirror image of the right side shown;

FIG. 5 is a rear view of the second embodiment;

FIG. 6 is an exploded perspective view of the second embodiment;

FIG. 7 is a top view of both the first and second embodiments; and,

FIG. 8 is a bottom view of both the first and second embodiments.

The cover and other features shown in broken lines are for illustrative purposes only and form no part of the claimed design.

1 Claim, 5 Drawing Sheets
